STORAGE TANK WITH PARTITIONED
FLOATING CLOSURE

Felix de Hoffmann, Buenos Aires, Argentina

Application May 12, 1949, Serial No. 92,799
In Argentina June 5, 1948

1 Claim. (Cl. 220—26)

1

The present invention refers to a storage tank for inflammable liquids, preferably petroleum and its derivatives, its essential object being to provide a storage tank which, owing to its excellent constructional features offers evident advantages over all other tanks or similar installations used or proposed to date for the same or similar purposes.

The disadvantages of the present usually employed tanks, of the open or closed kind used for storing petrol, its derivatives and other inflammable liquids, are well known, as well as their lack of safety in case of fire or spontaneous combustion of the contents.

In fact, the great difficulties encountered when trying to extinguish fire in such storage tanks are thoroughly familiar to all concerned. Such difficulties exist in spite of chemical methods and extinguishers used to put out the fire, and they are due, in the first place, to the great volume of liquid stored in each tank and the considerable surface of same, obliging the firemen to attack the conflagration simultaneously over a large zone—which is practically impossible. The consequence of this is that, in case of fire, the entire contents of the tank are practically destroyed, apart from the fact that the great heat generated by the inflamed mass, and the possibility of same exploding, can cause spontaneous combustion of fluids stored in adjacent tanks.

In order to avoid these drawbacks the improvement according to the present invention has been provided, consisting in dividing the free surface of the liquid in independent zones into smaller surfaces, so that in case of fire of the stored product, each one of said zones can be attacked independently, thus making it easier to put out the fire.

On the other hand, by independently arranging these separate zones, the fire can be isolated within one of same, it being possible, in certain cases, to prevent its spreading to adjacent zones, which also facilitates fire-extinguishing operations.

The invention likewise envisages other accessory objects that will be made clear during the course of the present description.

In order that the present invention may be more clearly understood and readily put into practice, same will now be described with refer-

2

ence to attached drawing, illustrating one of its preferred embodiments.

In the drawings, the figure illustrates an embodiment of my invention.

5 Like numerals represent like or similar parts throughout the several figures of the drawings.

In the embodiment shown in the drawings, 1 is an ordinary storage tank, the top part of which may be open or closed, as desired.

10 In accordance with the present invention, said tank 1 houses a structure consisting of a series of partitions 2 which are partially extended upwards and partially below the upper liquid level 3 of the fluid mass, said partitions forming a series of cells 4 wholly or partly covering the entire horizontal section of said tank.

Said partitions 2 are in turn joined together by means of a horizontal partition 5 limiting each one of said cells 4 from above. Said cells are 20 provided with openings 6 placed so as to coincide with the axes thereof. Said openings may be closed independently or conjointly by means of fixed or detachable covers 7, which in turn are provided with small ventilation holes or, as an alternative, can be kept slightly separated from partition 5 by means of small supports 8.

In the embodiment shown, the vertical partitions 2 as well as the horizontal one 5 are made of suitably separated double walls, so as to form 30 between them chambers 9 and 10, respectively.

The figure shows vertical partitions 2 are open at their lower ends, allowing the liquid to rise therein to a level indicated approximately by reference number 14, thus compressing within the upper chamber 15 of said partitions, a mass of air or of any other adequate fluid, the structure being in this manner made to float.

I claim:

40 A structure for the storage of inflammable liquids comprising a tank receiving the liquid, partition means in the tank and including a plurality of lower vertically disposed partitions with free bottom ends lying in a common horizontal plane immersed in the liquid and defining alter-
45 nately storage cells and parts of a buoyancy chamber, a plurality of pairs of spaced horizontal partitions, the lower partition of each pair closing the top of a storage cell, both partitions of each horizontal pair having concentric openings, a spacing tube connecting each hori-

horizontal pair of partitions at the margin of the openings therein, a plurality of upper vertically disposed spaced partitions each aligned in a common plane with a lower vertical partition and secured at its lower end to an upper horizontal partition and defining alternately an access chamber and part of the buoyancy chamber, a plurality of covers each aligned with a spacing tube and at spaced points supported by the top end thereof, and horizontal partition means closing the upper end of the buoyancy chamber.

FELIX DE HOFFMANN.
